Attorney.

UNITED STATES PATENT OFFICE.

SAMUEL A. HUTCHISON, OF OAK HILL, WEST VIRGINIA.

DESIGN FOR A BOX-HANDLE.

SPECIFICATION forming part of Design No. 27,247, dated June 22, 1897.

Application filed February 19, 1897. Serial No. 624,252. Term of patent 7 years.

To all whom it may concern:

Be it known that I, SAMUEL A. HUTCHISON, a citizen of the United States, residing at Oak Hill, in the county of Fayette and State of West Virginia, have invented and produced a certain new and original Design for Box-Handles; and I do declare the following to be a full, clear, and exact description of the invention, such as will enable others skilled in the art to which it appertains to make and use the same.

My invention relates to a design for a box-handle.

It relates to the entire configuration of the handle, and especially to the design for the box-handle illustrated in the accompanying drawing, in which the figure is a perspective view of a box-handle embodying my design.

The leading features of my design appear in the following description:

1 represents a rectangular case provided

with a plane side 2, converging walls 3 3, and a plane top 4, which joins the contiguous ends of the side 2 and converging walls 3 3.

5 5 represent diamond-pointed spurs projecting inwardly from the edges of the converging walls 3 3, and a corresponding diamond-pointed spur 6 extends inwardly from the top 4 and in the same plane as the spurs 5 5.

Having thus fully described my invention, 30 what I claim as new and useful, and desire to secure by Letters Patent of the United States, is—

The design for a box-handle, substantially as herein shown and described. 35

In testimony whereof I hereunto affix my signature in presence of two witnesses.

SAMUEL A. HUTCHISON.

Witnesses:

A. G. SEVY,
CHAS. F. MAHOOD.
